LOWE E. SIMPSON, OF CINCINNATI, OHIO, ASSIGNOR OF ONE-HALF TO ORVILLE SIMPSON, OF CINCINNATI, OHIO.

GAS-ENGINE.

1,231,799.

Specification of Letters Patent.

Patented July 3, 1917.

Application filed June 15, 1916. Serial No. 103,731.

To all whom it may concern:

Be it known that I, LOWE E. SIMPSON, a citizen of the United States, residing at College Hill, Cincinnati, Hamilton county, Ohio, have invented certain new and useful Improvements in Gas-Engines, of which the following is a specification.

This invention, relating to improvements in gas engines, will be readily understood from the following description taken in connection with the accompanying drawing in which:

Figure 1 is a horizontal section of a gas engine exemplifying my present improvements, the section being in the plane of line *b* of Figs. 2 and 3;

Fig. 2 a vertical section of the same in the plane of line *c* of Figs. 1 and 3;

Fig. 3 a vertical transverse section in the plane of line *a* of Figs. 1 and 2; and Fig. 4 a vertical section of a portion of the valve-casing in the plane of line *c* of Figs. 1 and 3.

In the drawing:

1, indicates the cylinder of a four-cycle gas engine;

2, the crank-bearings of the crank-shaft;

3, the crank-shaft;

4, the crank-pin;

5, the circular path of the crank-pin;

6, the piston;

7, the connecting-rod connecting the piston and crank-pin;

8, a cylindrical valve-casing;

9, a fuel inlet communicating with the interior of the valve-casing;

10, a plurality of ports connecting fuel inlet 9 with the interior of the valve-casing;

11, an exhaust outlet from the valve-casing;

12, a circular series of ports placing exhaust outlet 11 in communication with the interior of the valve-casing;

13, an air inlet for the valve casing;

13^a, a plurality of ports leading from air inlet 13 into the valve-casing;

14, the combustion-chamber of the engine;

15, the cylinder-head of the engine, this cylinder-head, in the illustration also containing the valve-casing;

16, the passage leading from the valve-casing to the combustion-chamber of the engine;

17, the water-jacket of the engine-cylinder;

18, a hollow sleeve-valve fitting and slid-

ing within the valve-casing, its inner end co-operating with ports 12:

19, a circumferential series of ports through the wall of sleeve-valve 18, and co-operating with inlet-ports 10 and 13^a:

20, a piston-valve fitting and sliding within the sleeve-valve, its inner end having valvular co-operation with ports 19:

21, a valve-operating crank-shaft;

22, transmission mechanism, illustrated as 65 a shaft and bevel gearing, connecting the crank-shaft of the engine with the valve-operating shaft in such manner that the valve-operating shaft will make one rotation to two rotations of the crank-shaft of 70 the engine:

23, the crank-pin of the valve-operating crank-shaft;

24, a link connecting this crank-pin with piston-valve 20:

25, a stationary pivot:

26, the two pivotally connected members of a toggle connecting pivot 25 with sleeve-valve 18:

27, a link connecting crank-pin 23 with 80 the intermediate pivot 29 of toggle 26:

28, the spark-plug; and

29, the intermediate pivot of the toggle 26.

As thus far described the functioning of the valve-members and the operation of the 85 engine would be as usual, and analysis of the movements of the valves will show that in the course of these movements they admit the fuel and air to the combustion-chamber and permit the burned gases to exhaust from the combustion-chamber at proper times. These functional results are not original with the present invention but have been before accomplished by known mechanism.

The valve-operating crank-shaft 21 actuates piston-valve 20 through the medium of link 24, while it actuates sleeve-valve 18 through the medium of link 27 and the toggle 26. Links 24 and 27 are independent 100 of each other though a first glance suggests that they constitute a bellcrank. The general regimen of the valvular parts brings about the results usual in gas engines of the four-cycle type, that is to say, the inlet is 105 opened; the piston moves through its suction stroke; fuel and air are sucked into the cylinder; the inlet closes; the piston makes its compressing stroke; the compressed mixture is ignited; the piston moves through 110

its power stroke; the exhaust opens; the piston moves through its exhaust stroke; the spent gases are forced out of the engine; the exhaust closes; and so on and on.

5 The mechanism comprising the toggle 26 and link 27 provides a simple and economically constructed means through which the valve-operating crank-shaft may give motion to the sleeve-valve, and analysis will 10 show that the valve-operating mechanism brings about the desired valvular movements in the most desirable and efficient manner.

Proceeding with the drawings:—

15 30, indicates an adjustable carrier for the stationary end pivot 25 of the toggle:

31, a screw for adjusting this carrier:

32, a handle for turning the screw:

33, the arc in which pivot 29 moves when pivot 25 is in the position indicated in full 20 lines in Fig. 3: and

25 34, the arc in which toggle-pivot 29 will move if pivot 25 be adjusted to the position indicated in dotted lines in Fig. 2.

Assuming pivot 25 to be in the position indicated in full lines in Fig. 2, the intermediate toggle-pivot 29 will sweep in arc 33 and bring about certain functional movement of the sleeve-valve 18 appropriate to a given speed of engine. If, now, pivot 25 be 30 adjusted to the position indicated in dotted lines, the intermediate toggle-pivot 29 will move in arc 34, causing pivot 29 to move farther toward and farther from the valve-casing, thus modifying the time of opening and 35 closing brought about by the reciprocations of the sleeve-valve and rendering its functioning appropriate to a higher speed of the engine.

It is to be noted that carrier 30 of pivot 40 25 has a sliding adjustment in a right line at an angle of about forty-five degrees to the axis of the sleeve-valve and that the adjustment is effected by means of a screw. Neither the adjustment of the pivot 25 by 45 hand or in a right line, or a screw as a means for effecting the adjustment, are essential to a realization of my invention.

It is to be noted, in Fig. 3, that ports 10 and 13^a admitting gas and air to the valve-50 casing are arranged tangentially to the axis of the valve-casing. This arrangement of the ports causes the gas and air to enter the valve-casing with a swirling motion tending to enhance the commingling of these components of the combustible mixture before they 55 go to the combustion chamber.

Gas reaching the valve-casing from gas-inlet 9 does so through ports 10, illustrated as being two in number in a circumferential 60 series of ports entering the valve-casing, while air entering the valve-casing from air inlet 13 does so through ports 13^a, illustrated as being six in number in the same circular series with the ports 10 which admit the gas 65 to the valve-casing.

If, in a gas engine, a combustible mixture is admitted at the initiation of the suction-stroke of the piston, the mixture may possibly be ignited by the fire in the residual gases, which would be highly undesirable, 70 the desire being to have no ignition until the mixture has been received into the cylinder and compressed by the engine piston. In recognition of this it has been common to admit air on the suction stroke before any 75 gas was admitted, and this is accomplished in a very simple manner in the present construction. The admission of the gas and air to the combustion-chamber is accomplished by the leftward movement of the 80 sleeve-valve, the ports 19 in its wall co-operating with the gas-ports 10 and the air-ports 13^a. The left hand margins of the ports 10 and 13^a are in the same plane, but ports 10, for the gas are shorter than ports 13^a for the 85 air, as shown in Fig. 4. The consequence of this arrangement is that as the sleeve-valve 18 moves to the left it will place air-ports 13^a in communication with the combustion-chamber for some period of time before gas-ports 90 10 are placed in communication with the combustion-chamber, and that by the time the admission to the combustion-chamber comprehends a combustible mixture the danger of premature ignition from the residual 95 gases can be over.

An analysis of the valves and their actuating mechanism will show that an adjustment of the toggle-pivot 25, from its position indicated in full line appropriate to a given engine speed, toward its position indicated in dotted line, appropriate to a higher engine speed, brings about the retarding of the opening of the intake, the retarding of the closing of the intake, the advancing of the opening of the exhaust, and the retarding of the closing of the exhaust.

I claim:—

1. A gas engine comprising, a valve-casing provided with inlet and outlet ports, a sleeve-valve fitted to slide within the valve-casing and having ports through its wall adapted to co-operate with the inlet ports of the valve-casing and having its end adapted to co-operate with the outlet ports of the 110 valve-casing, a piston-valve fitted to slide within the sleeve-valve and have its end co-operate with the ports through the sleeve-valve, a valve-moving crank, a link connecting the pin of said crank with the piston-valve, a stationary pivot, a toggle having one of its extremities connected with said stationary pivot and having its other extremity connected with the sleeve-valve, and a link connecting the intermediate pivot of the toggle with the pin of the valve-moving crank, combined substantially as set forth.

2. A gas engine comprising, a valve-casing provided with inlet and outlet ports, a sleeve-valve fitted to slide within the valve- 120

casing and having ports through its wall adapted to coöperate with the inlet ports of the valve-casing and having its end adapted to cooperate with the outlet ports of the 5 valve-casing, a piston-valve fitted to slide within the sleeve-valve and have its end coöperate with the ports through the sleeve-valve, a valve-moving crank, a link connecting the pin of said crank with the piston-

10 valve, a stationary pivot, a toggle having one of its extremities connected with said stationary pivot and having its other extremity connected with the sleeve-valve, a link connecting the intermediate pivot of the 15 toggle with the pin of the valve-moving crank, and means for adjusting said stationary pivot, combined substantially as set forth.

3. A gas engine comprising, a valve-casing 20 provided with inlet and outlet ports, a first valve-member fitted to slide relative thereto and having a port through it adapted to coöperate with the inlet-port of the valve-casing and having its end adapted to coöperate with the outlet-port of the valve-casing, a second valve-member fitted to slide 25 relative to the first valve-member and have its end coöperate with the port thereof, mechanism for moving the two valve-members relative to each other and to the valve-casing, and means, operable while the valve-members are in motion, for adjusting the 30 time of the opening and closing of the inflow and outflow effected by the valve-members, combined substantially as set forth.

4. A gas engine comprising, a valve-casing 35 provided with a gas-inlet and with a series of ports leading therefrom to the interior of the valve-casing and with an air-

inlet and a series of ports leading therefrom to the interior of the valve-casing, one of the margins of the gas-inlet ports lying in a different plane from the corresponding margin of the air-inlet ports, a sleeve-valve fitted to reciprocate within the valve-casing and having ports through its wall adapted to first open the air-ports in the valve-casing and later open the gas-ports in the valve-casing, and a piston-valve fitted to reciprocate within the sleeve-valve and having its end adapted to coöperate with the ports in the sleeve-valve and to cause the intake of gas and air to be simultaneously closed, combined substantially as set forth.

5. A gas engine comprising, a valve-casing 55 provided with a gas-inlet and with a port leading therefrom to the interior of the valve-casing and with an air-inlet and a port leading therefrom to the interior of the valve-casing, one of the margins of the 60 gas-inlet port lying in a different plane from the corresponding margin of the air-inlet port, a sleeve-valve fitted to reciprocate within the valve-casing and having a port through its wall adapted to first open the 65 air-port in the valve-casing and later open the gas-port in the valve-casing, and a piston-valve fitted to reciprocate within the sleeve-valve and having its end adapted to coöperate with the port in the sleeve-valve and to cause the intake of gas and air to be 70 simultaneously closed, combined substantially as set forth.
